CENTRIFUGALLY CONTROLLED SLIP SWITCH

Application filed October 25, 1930. Serial No. 491,274.

This invention relates to switch operating mechanism adapted for application to reversible shafts, the purpose of the invention being to provide means for opening or closing a circuit automatically when the shaft slows down and before it starts in the reverse direction.

The invention is adapted particularly for use as an aid in the stoppage of induction motors. Thus, where a dynamic braking action is applied to an induction motor of the wound-rotor type, to stop the motor by temporarily reversing the current phases in the rotor circuits, in well known manner, the mechanism of the present invention may be used to cause the interruption of the braking circuit at a predetermined time before the rotor of the motor comes to rest.

In the accompanying drawings, which illustrate the invention,

Fig. 1 is a side elevation of the mechanism embodying the invention, partly broken away, the casing being shown in vertical section and the parts being shown in normal positions;

Fig. 2 is a top plan view of the switch;

Fig. 3 is a top plan view of the switch operating mechanism, the shaft being partly broken away and the parts being shown in normal positions;

Fig. 4 is a section on the line of 4—4
Fig. 3;

Fig. 5 is a section the same as in Fig. 4, but showing the relation of the parts when the motor shaft is turning;

Fig. 6 is a section on the line 6—6 of Fig. 1;

Fig. 7 is a side elevation of the movable friction disk;

Fig. 8 is a perspective view of one of the links connecting the centrifugal governor with the sliding cone;

Fig. 9 is a side elevation of the cone; and,

Fig. 10 is a similar view of the sleeve upon which the various parts are mounted.

Referring to the drawings *a* indicates a casing, in the opposite sides of which are bushings 1 which form bearings for a shaft 2 which extends through the casing and is provided at one end with a driving pulley 3.

Upon the shaft, and rotatable therewith, is a

centrifugally operated device *b* and a friction device *c* which is frictionally clutched to the shaft and released therefrom by the operation of the governor. Above this mechanism a switch *d* is mounted on a base or panel 4, of insulating material, which is supported by brackets 5 on the side walls of the casing. An arm 6 projects upwardly from the friction device through a slot 7 in the switch base and into a fork 8^a at one end of a switch lever 8, which lever is centrally pivoted on a post 9 and adapted to swing parallel with the top surface of the base. Upon the end of the lever opposite the fork 2, contact members 10 and 11 are loosely pivoted upon a pin 8^b which extends through the lever. These contact members are alike, each U-shape in transverse section and having contact buttons on their outer edges. Thus, the member 10 has contact buttons 10^a adapted to engage a pair of stationary contacts 12 and 13, and the member 11 has contact buttons 11^a adapted to engage a pair of spaced stationary contacts 14 and 15. The stationary contacts, being arranged on opposite sides of the lever, as shown, serve as stops to limit the movements of the lever, and each contact member on the lever is adapted to electrically connect or bridge one pair of stationary contacts.

As shown Figs. 1 and 2 of the drawings a light spring 16 is connected to a stationary pin 17 near one end of the slot 7, and to an eye 18 on one side of the switch lever between its pivotal point and the end of the lever which carries the contact members, and this spring normally holds the lever in the position shown in full lines, with its contact member 11 against the stationary contacts 14 and 15. If it is desired to have the contact member 10 normally held against the stationary contacts 12 and 13, the spring will be removed from the pin 17 and eye 18 and connected to a pin 19 at the opposite end of the slot 7 and to an eye 20 opposite the eye 18. In the drawings, wires 21 and 22 are shown connected to the contacts 12 and 13, and these may lead to a relay or contactor which controls the braking circuit of a motor which drives the shaft 2. This circuit is normally open at said contacts, but is closed when the

lever is moved into the dotted line position by the movement of the arm 6.

The arm 6 projects radially from a friction disk 23, of carbon-graphite compound, which is loosely journaled upon one end 24 of a sleeve *e* which is secured to the shaft 2 by a set screw 25. The disk 23 fits snugly within a peripheral metal band 26 and the end of the arm is threaded into this band and extends

5 into the disk, thereby locking the parts together. A metal washer 27 is secured tightly to the sleeve at one side of the friction disk and a washer 28, at the opposite side of the disk, is keyed to the sleeve so as to rotate with it, but is movable longitudinally of the sleeve into and out of engagement with the friction disk. As shown, the sleeve has a longitudinal slot 29, and a tongue 28^a on the washer projects into this slot.

10 The sleeve *e* has a cylindrical part 24 at one end upon which the friction disk and washers are mounted, a central cylindrical portion 24^a of larger diameter, and the end portion 24^b is rectangular in cross section and 15 of larger diameter than the central portion. A shallow annular groove 30 is formed in the end of the central portion, adjacent washer 28, and an endless helical spring 31 rests normally in this groove.

15 The sleeve *e* has a cylindrical part 24 at one end upon which the friction disk and washers are mounted, a central cylindrical portion 24^a of larger diameter, and the end portion 24^b is rectangular in cross section and 20 of larger diameter than the central portion. A shallow annular groove 30 is formed in the end of the central portion, adjacent washer 28, and an endless helical spring 31 rests normally in this groove.

25 A block *f*, having a central bore, is slidably mounted on the part 24^a of the sleeve and has a conical end 32 adapted to extend within the annular spring and force the latter out of the groove and against the washer 28. As the 30 block or sleeve *f* is forced toward the washer the spring expands radially and presses evenly against the washer along a circular line so that the inner face of the washer bears with equal pressure at all points against the friction disk. The tension of the spring on the tapering surface of the block or sleeve *f* tends to force the block away from the washer toward the end 24^b of the sleeve. When the 35 block is moved to the latter position the spring contracts and rests in the groove 30 and the lateral pressure against the washer 32 is relieved, as also the pressure of the washer against the friction disk.

40 The block *f* rests against the part 24^b of the sleeve when the shaft is stopped, as indicated in Figure 4, and it is automatically forced into position to expand the spring by the centrifugal governor *b* when the shaft is rotated. This governor comprises two similar 45 flat weights 33, these weights being held parallel with one another and spaced apart by posts 34 which are riveted to the weights. The weights have central threaded openings 35 and the posts are diametrically opposite 50 these openings. Screws 36, threaded into the openings, have pintles 37 on their inner ends which enter a bore 38 in the rectangular part 24^b of the sleeve *e*. This bore extends through the sleeve at right angles to two of its sides 55 and in line with the axis of the shaft 2. Be-

tween the squared portion of the sleeve and the weights are arranged links 39 one of which is shown in Figure 8. Each link has a pintle 39^a at one end and a slot 39^b at the opposite end. These pintles extend into openings 40 in the weights near the axis of the weights and the slotted ends of the links engage pins 41 on opposite sides of the sliding block or sleeve *f*.

60 It will be evident that when the shaft is rotated above a certain minimum speed the weights will turn about their axis and the links will be moved to press the block *f* toward the friction devices. The spring 30 is expanded by this movement and rides up on the conical part of the block. As the shaft speed slows down, the pressure of the spring against the conical end of the block forces the block toward the axis of the weights and the links rock the weights to their normal position, shown in Figures 1 and 4, before the shaft stops.

65 To limit the movement of the weights and avoid shock, when the shaft is started, a yielding stop is provided on the part 24^b of the sleeve. This stop consists of a rigid metal strip 42 and a resilient metal strip 43, both secured at one end to the part 24^b by a screw 44, and both bent outwardly from said part, as shown. The projecting ends of the strips 70 lie in the path of movement of the adjacent post 34, with the resilient strip spaced from the rigid strip so that it will cushion the blow of the post as the weights swing outwardly and before they are arrested by the more 75 rigid strip.

80 The operation is as follows: The motor to be controlled, or some part driven by the motor, is belted to the pulley 3 so as to drive the shaft 2 at a moderate speed when the motor is in operation. If the shaft is to turn in the direction of the arrow, Figure 1, the spring 16 will be connected as shown in Figure 2 and the contact member 10 will be normally held away from contacts 12 and 13 85 and the arm 6 of the friction device will be held in the position shown in full lines in said figure. When the motor starts, the rotation of the shaft 2 will cause the centrifugal device to swing about its axis from the 90 position shown in Figure 4 to the position Figure 5 and the sleeve or block *f* will wedge the helical spring out of the groove 30 and against the washer 28, which latter will bear against the friction disk with sufficient force 95 to rotate the latter and the arm 6 will swing the switch arm 8, against the tension of the spring 16, from the full line position in Figure 2 to the dotted line position, wherein the contact member 10 abuts against the stationary contacts 12 and 13 and electrically connects said contacts. The friction device will hold the switch in this closed position as long 100 as the shaft is driven in the direction indicated and at a speed above a certain low 105

110

115

130

speed. When the motor is slowed down, as by applying a braking current to it, the shaft 2 slows down and the pressure exerted against the block *f* by the centrifugal device decreases. This permits the spring 31 to contract, and in contracting its pressure against the conical surface of the block forces the latter away from the friction device, and the block, acting through the links 39 rocks 10 the weights of the centrifugal device to normal position just before the shaft 2 stops. As shown in Figure 4, the spring 31 contracts into the groove 30 immediately before the shaft stops and the pressure of the spring 15 against the washer 28 is relieved so that the latter no longer bears against the friction disk. As soon as the pressure of the washer against the disk is sufficiently relieved, the spring 16 moves the switch lever 8 and the 20 arm 6 of the friction device back to normal positions as illustrated in full lines in Figure 2, and the circuit is opened at the contacts 12 and 13.

Thus it will be seen that the circuit which 25 is held closed while the motor is running normally, is opened immediately before the motor comes to rest.

If it is more convenient to have the shaft 2 turn in the opposite direction from that indicated by the arrow in Figure 1, or clockwise, as viewed from the pulley end of the shaft, the spring 16 will be shifted so as to connect the eye 20 on the lever with the stationary pin 19, and the circuit wires 21 and 22 30 will be transferred to the contacts 13 and 14. The switch lever will then normally lie in the dotted position Figure 2, with the switch open at the contacts 14 and 15, and when the motor is started the friction device will move 35 its arm 6 and the switch lever to the full line position wherein the circuit will be closed at the contacts 14 and 15 by the contact member 11. When the motor slows down, and just before the shaft 2 stops, the friction 40 device will be released and the spring on the switch will return the switch lever to the dotted position.

What I claim is:

1. Circuit controlling means comprising a 50 shaft, a friction member rotatable about the shaft, a switch operable by said member, a device rotatable with the shaft and adapted to frictionally engage said member, and centrifugally-operated means adapted to force said device into frictional engagement with said member when the shaft is rotated above a certain low speed and to release said device when the shaft slows down and before it stops.

60 2. Circuit controlling means comprising a shaft, a friction disk rotatable about the shaft, a switch operable by said disk, a washer rotatable with the shaft and adapted to frictionally engage the disk, a centrifugal governor and means operated thereby for

yieldingly pressing said washer against said disk when the shaft is rotated above a certain low speed and for releasing the pressure on the washer when the shaft slows down and before it stops. 70

3. Circuit controlling means comprising a shaft, a friction disk rotatable about the shaft, a switch operable by said disk, a washer rotatable with the shaft and movable to frictionally engage said disk, a spring adjacent the washer and centrifugally-operated means adapted to force said spring against said washer when the shaft is rotated and to release the pressure on the spring when the shaft slows down and before it stops. 75

4. Circuit controlling means comprising a shaft, a friction disk rotatable about the shaft, a switch operable by said disk, a washer rotatable with the shaft and movable to frictionally engage said disk, an annular helical spring surrounding the shaft adjacent the washer, a member slidable longitudinally of the shaft and having a conical surface adapted to enter and expand said spring radially and force it against the washer, and a centrifugal device adapted to move said slidable member into position to expand the spring 85 when the shaft is rotated. 90

5. Circuit controlling means comprising a shaft, a friction disk rotatable about the shaft, a switch operable by said disk, a washer rotatable with the shaft and movable to frictionally engage said disk, an annular helical spring surrounding the shaft adjacent the washer, a member slidable longitudinally 95 of the shaft and having a conical surface adapted to enter and expand said spring radially and force it against the washer, and a centrifugal device adapted to move said slidable member into position to expand the 100 spring when the shaft is rotated, said spring adapted to contract on said conical surface and force said slidable member and the centrifugal device to normal positions when the shaft slows down and before it stops. 105

6. Circuit controlling means comprising a shaft, a friction disk rotatable about the shaft, a switch operable by said disk, a washer rotatable with the shaft and movable to frictionally engage the disk, an annular helical spring surrounding the shaft adjacent the washer, a member slidable longitudinally of the shaft and having a conical end adapted to enter and expand the spring, a centrifugal device having rocking parts on opposite sides 115 120 of the shaft, and links connecting said parts with said member.

7. Circuit controlling means comprising a shaft, a friction disk rotatable about the shaft, a switch operable by said disk, a washer 125 rotatable with the shaft and movable to frictionally engage the disk, said shaft having an annular groove adjacent the washer, an annular helical spring normally resting in said groove, a member slidable longitudinally of 130

the shaft and having a conical end adapted to lift the spring out of the groove and expand it against the washer, and a centrifugal device adapted to force said member toward the washer when the shaft is rotated.

8. Circuit controlling means comprising a shaft, a sleeve secured to the shaft, a friction member rotatable about the sleeve, a switch operable by said member, a device rotatable with the sleeve and adapted to frictionally engage said member, said sleeve having an annular groove adjacent said device, an annular helical spring normally resting in said groove, a member slidable on the sleeve and having a conical end adapted to lift said spring from the groove and expand it against said device, and a centrifugal device mounted on the sleeve and adapted to force said member into said spring when the shaft is rotated.

9. Circuit controlling means comprising a shaft, a friction member rotatable about the shaft, a switch member biased to open position, connections between said members whereby they move together, a device rotatable with the shaft and adapted to frictionally engage said friction member, and centrifugally operated means adapted to press said device into frictional engagement with said friction member when the shaft is rotated above a certain low speed and to release said device when the shaft slows down and before it stops.

10. Circuit controlling means comprising a shaft, a friction member rotatable about the shaft, a centrally pivoted switch lever, means whereby said lever may be resiliently pressed to either of two positions, an arm connecting said friction member with said lever so that they will move together, a device rotatable with the shaft and adapted to frictionally engage said friction member, and centrifugally operated means adapted to press said device into frictional engagement with said friction member when the shaft is rotated above a certain low speed and to release said device when the shaft slows down and before it stops.

In testimony whereof I affix my signature.
50 GEORGE H. WHITTINGHAM.
